THREAD-CUTTING MECHANISM FOR
SEWING MACHINESAlfred R. Wood, Bridgeport, Conn., assignor to
The Singer Manufacturing Company, Elizabeth, N. J., a corporation of New Jersey

Application August 21, 1945, Serial No. 611,723

14 Claims. (Cl. 112—252)

1

This invention relates to group-stitching sewing machines, such for example as buttonhole machines or tacking machines, and more particularly to the thread-cutting mechanism of the machine, which mechanism is designed not only to cut the needle-thread close to the work at the end of a sewing operation and hold the beginning end of the needle-thread for the beginning of the next sewing operation, but also to retrim the beginning end of the needle-thread close to the work, so that both ends of the needle-thread will be uniformly trimmed.

In sewing machines of the type to which the present invention pertains, it is customary to provide the upper member of the work-clamp with a combination thread-cutting and -nipping blade which is actuated at the end of the sewing operation to cut and nip the needle-thread. This thread-cutting and -nipping blade holds the beginning end of the needle-thread during the sewing of slightly more than half of the stitching cycle. As the sewing proceeds to complete the operation and nears the starting point, this blade is retracted to get it in readiness to cut the needle-thread after the stitching cycle is completed. When the blade is retracted, however, it releases the beginning end of the needle-thread which, in view of its length, is in a position to be sewed-in or bound down by the final stitches of the buttonhole or tack. In view of this condition, there is a certain lack of uniformity in the product of such a machine resulting from the fact that the beginning end is not disposed of and may at times protrude to an unsightly extent necessitating hand retrimming.

To eliminate the necessity of this hand retrimming, the combination thread-trimming and -nipping blade is operated twice for each complete stitching cycle, once before the sewing is completed, preferably after slightly more than one-half of the stitching cycle is completed, when it is safe to release the beginning end of the needle-thread, and a second time after the sewing is completed. The first operation of the blade retrims the beginning end of the needle-thread and the second operation trims the finishing end of the needle-thread; both ends being thus uniformly trimmed close to the work.

In prior machines, the resetting of the trimmer-blade preparatory to the final thread-cutting and -nipping operation is effected by utilizing solely the longitudinal shifting of the work-clamp relative to the bed of the machine to bring the usual trimmer-blade retracting push-rod carried by the work-clamp into contact with

2

a fixed abutment member. Inasmuch as the longitudinal shifting of the work-clamp is effected in a step-by-step manner, the resulting relatively slow retraction of the trimmer-blade in a plane perpendicular to the path of needle-reciprocation requires that the trimmer-blade be swung beyond the range of the needle before the work-clamp is shifted to a point such that collision can occur between the needle and trimmer-blade. This condition limited the capacity of the machine, since it prevented the machine from producing buttonholes or tacks smaller than a certain size. In an effort to increase the capacity of the machine, the length of the needle-thread trimmer-blade was reduced, but this introduced the possibility of the trimmer-blade missing the needle-thread when it was swung to trim the finishing end of the needle-thread.

It is the primary object of the present invention to provide means effecting a rapid retraction of the combination needle-thread-trimming and -nipping blade for the purpose of resetting the blade for its final thread-cutting and -nipping operation.

Another object of the invention is to provide a needle-thread-trimming and -nipping blade retracting mechanism designed to operate with such rapidity that the blade may be swung into its reset position after the blade has been shifted within the range of the needle.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

40 In the drawings,

Fig. 1 is a fragmentary right side elevational view of a straight buttonhole sewing machine equipped with the present invention.

Fig. 2 is a top plan view, partly in section, of 45 the bed of the machine shown in Fig. 1, illustrating the location of the thread-trimming device and the operating mechanism therefor when the machine is performing the first portion of the stitching cycle.

Fig. 3 represents an enlarged vertical sectional view taken substantially along the line 3—3, Fig. 2, showing the way in which the needle-thread beginning end is held nipped.

Fig. 4 represents a top plan view, partly in section, of the needle-thread trimmer, illustrating

the trimmer-blade in set position preparatory to the retrimming of the beginning end of the needle-thread.

Fig. 5 represents a vertical sectional view similar to Fig. 3, but showing the relatively long released beginning end of the needle-thread.

Fig. 6 is a view similar to Fig. 5, but showing the needle-thread beginning end retrrimmed to its final short length.

Fig. 7 is a view similar to Fig. 4, but showing the trimmer-blade in its reset position preparatory to its final thread-cutting and -nipping operation.

Fig. 8 represents an enlarged perspective view of the cam-element employed for actuating the trimmer operating mechanism so as to swing the trimmer-blade into its set and reset positions.

Fig. 9 represents an enlarged perspective view of the cam-locking disk which is employed for securing the actuating cam-element in any one of a plurality of selected positions determined by the length of the buttonhole or tack to be produced.

Fig. 10 represents an enlarged vertical, sectional view taken substantially along the line 10—10, Fig. 1.

Fig. 11 represents an enlarged left side elevational view of the trimmer-blade retracting push-rod and its latching expedient.

In the preferred embodiment of the invention, the buttonhole sewing machine illustrated in the drawings comprises a frame including a bed 1 supporting a standard 2 of an overhanging bracket-arm terminating in a head 3. Mounted in the head 3 is a vibratory gate 4 carrying an endwise reciprocating needle-bar 5 fitted at its lower end with an eye-pointed thread-carrying needle 6. The needle-bar 5 derives its reciprocation from the usual actuating connections within the head 3, which connections are operated from the main- or arm-shaft (not shown) of the machine. The arm-shaft is connected by a vertical shaft 7 and gearing 8 to a loop-taker shaft 9 adapted to carry at its outer end a rotary loop-taker (not shown) for cooperation with the needle 6 in the formation of stitches.

The work W to be buttonholed is adapted to be held in a work-clamp comprising the usual lower work-plate 10 and an upper clamp-foot 11. The upper clamp-foot 11 is carried by the two resilient arms 12 and 13 which are secured at their inner ends on a yoke 14 pivoted at 15 to a lug 16 upstanding from the longitudinal slide-plate 17. The upper clamp-foot 11 is yieldingly urged downwardly into contact with the lower work-plate 10 by a coil-spring 18. To provide for separating the upper clamp-foot 11 from the lower work-plate 10 for the insertion and removal of work, the yoke 14 is formed with a rearwardly extending tail-lever 19 adapted to underlie a roller 20 (Fig. 2) carried intermediate the ends of a manually actuated lever 21 fulcrumed at one end on a stud 22 threaded into the supporting bracket 23. At its other end, the lever 21 is fitted with a horizontally disposed stud 24 to the free end of which is attached a suitable treadle-chain connection-element 25. Depression of a suitable foot-treadle will cause the lever 21 to swing on the stud 22, against the action of a spring 26, thus causing the roller 20 to engage the tail-lever 19 and swing the yoke 14 about its fulcrum 15, thereby raising the arms 12 and 13 and the upper clamp-foot 11.

To effect shifting of the work relative to the endwise reciprocating and laterally vibratory needle 6, the work-clamp is slowly moved in step-

by-step fashion, first away from the standard 2 and then towards the standard to cause the first and second rows of side zigzag stitches to be laid side by side in the work. The work-clamp derives its step-by-step movements from the usual feed-cam 27 carried on a vertically disposed feed-shaft 28 journaled in the bed and the bracket-arm of the machine. The connections between the work-clamp and the feed-cam are identical with those disclosed in my co-pending application Serial No. 545,035, filed July 15, 1944. The feed-cam 27 and the feed-shaft 28 are intermittently rotated by means of a one-way-acting clutch 29, of the well-known Horton type, which clutch is driven during the operation of the machine by means of an actuating lever 30 connected by a link 31 to a rock-lever 32 carried by the lower end of a vertically disposed rock-shaft 33 (Fig. 1) journaled in a bearing bushing 34 pressed into the machine-bed 1. At its upper end, the rock-shaft 33 has secured to it a second rock-lever 35 connected to a pitman 36 which embraces an eccentric 37 fast on the vertical shaft 7. As the shaft 7 is rotated, the eccentric 37 imparts to the rock-shaft 33 oscillatory movements which, through the rock-lever 32, link 31 and actuating lever 30, operate the clutch 29. The clutch drives the feed-cam 27 and the feed-shaft 28 intermittently in one direction.

The needle-thread trimming and nipping mechanism now to be described comprises a trimmer-blade 38 and a nipping-blade 39 (Figs. 3 and 6), the shanks of which are secured by a screw 40 in a cross-slot 41 provided in a head 42 formed at the lower end of the usual vertical rock-shaft 43 journaled in the upper clamp-plate 11. This construction is substantially the same as that disclosed in the U. S. patent of E. B. Allen, No. 885,310, dated April 21, 1908. The needle-thread trimming and nipping-blades 38 and 39 are adapted to operate in a slot 44 defined by the under surface 45 of the upper clamp-plate 11 and the surface 46 of a hardened detachable section 47 secured to the clamp-plate 11. The nipping-blade 39 cooperates with the surface 45, as shown in Fig. 3, to hold the beginning end of the needle-thread during the sewing of the first portion of the buttonhole. The trimmer-blade 38 has a sharpened edge which cooperates with an edge of the surface 46 of the detachable section 47 in severing the needle-thread.

The trimmer-blade carrying rock-shaft 43 has fixed on its upper end a rock-arm 48 connected to the outer end of a trimmer-blade actuating member or retracting push-rod 49 disposed in the direction of the longitudinal travel of the work-clamp and endwise slidably supported adjacent its inner end in an upstanding ear 50 integral with a plate 51 secured by screws 52 on the yoke 14. The ear 50, in addition to serving as a support for the push-rod 49, also functions in conjunction with a fixed collar 53 and resilient pad 54 on the push-rod 49 as a stop to limit the endwise movement of the push-rod under the action of a coil-spring 55 acting between the ear 50 and another fixed collar 56 on the push-rod 49. The coil-spring 55 normally functions to maintain the parts in the position shown in Figs. 2 and 3, in which position the beginning end of the needle-thread is nipped and the resilient pad 54 of the collar 53 is against the ear 50.

To produce the necessary endwise movement of the push-rod 49 for actuating the thread-trimming and nipping blades 38 and 39 to effect the release of the nipped beginning end of the

needle-thread and to set the trimmer-blade preparatory to the retrimming of the beginning thread-end, there is provided a cam-actuated linkage. This linkage comprises a lever 57 pivoted at one end on a stud 58 threaded into a lateral extension 59 provided on the supporting bracket 23. The other end of the lever 57 is upturned, as at 60, to engage a block 61 (Fig. 4) adjustably secured on the push-rod 49. The lever 57, intermediate its ends, is connected by a link 62 to a second lever 63 pivoted at 64 on the lateral extension 59 and having a cam-follower nose 65 which is maintained by a spring 66 in contact with an actuating cam 67 integral with an actuating device or cam-element 67' mounted on the feed-shaft 28. The actuating cam 67 is formed with a gradual rise 68 terminating in a sharp drop-off 69; the timing of the drop-off 69 being regulated through the medium of a timing pin 70 adapted to be yieldingly pressed into a selected one of a number of timing holes 71 provided in a disk 72 fast on the feed-shaft 28. On the rim of the disk 72, each of the timing holes 71 is identified by a number from one to thirteen, corresponding to a similar number employed on the adjusting device of the mechanism connecting the feed-cam 27 with the work-clamp, which number indicates the length of buttonhole to which the machine is adjusted to produce. For a disclosure of this adjusting device, reference may be had to my above mentioned co-pending application Serial No. 545,035. To effect an adjustment of the timing of the cam 67 to conform with an adjustment of the work-clamp shifting mechanism, the cam-element 67' is lifted by its knurled hub 73, in opposition to a coil-spring 74 (Fig. 1), and turned relative to the feed-shaft 28 until the pin 70 is in register with the desired timing hole 71, after which the knurled hub 73 is released. The coil-spring 74 maintains the pin 70 in the selected timing hole 71, thus locking the cam-element 67' to turn with the feed-shaft 28.

When the machine is started, the component parts of thread-trimming mechanism are in the position shown in Fig. 2, with the beginning end of the needle-thread held nipped as shown in Fig. 3. As the sewing progresses down the first side of the buttonhole, the feed-shaft 28 is turned slowly, causing the gradual rise 68 of the cam 67 to swing the lever 57, through the lever 63 and link 62, so that its upturned end 60 engages the block 61 on the push-rod 49 and shifts the latter into the position shown in Fig. 4. In this position of the push-rod 49, the trimmer-blade 38 and the nipping-blade 39 have been swung into open position, in which position the beginning thread-end is released as shown in Fig. 5, and the trimmer-blade is set for its retrim stroke. As the machine continues to operate, the cam 67 is turned to the point where its drop-off 69 passes the nose 65 of the lever 63. When this occurs, the coil-spring 55 snaps the push-rod 49 endwise and in a direction to close the trimmer-blade 38 upon and retrim the beginning end of the needle-thread to the length clearly shown in Fig. 6.

To provide for reopening or resetting the trimmer-blade 38 preparatory to the trimming of the finishing end of the needle-thread and nipping the beginning end of the needle-thread for the beginning of the next sewing operation, I have provided a second cam-actuated linkage or lever arrangement, the components of which are designed and proportioned to perform its intended function rapidly and efficiently. To this end, the

cam-element 67' is provided with a second actuating cam 75 adapted to engage a cam-follower-nose 76 formed on the free end of one of the arms of a two-arm lever 77 fulcrumed at 78 on the machine-standard 2. The other arm of the lever 77 has secured to it a roller 79 arranged to enter an elongated slot 80 formed in the shorter limb of an L-shaped lever 81 fulcrumed at 58 on the lateral extension 59 of the supporting bracket 23. The longer limb of the lever 81 terminates in a downturned end 82 adapted to be moved into engagement with the block 61 on the end of the push-rod 49. As will be seen in Fig. 4, the cam 75 is positioned relative to the cam 67 so that shortly following the action of the trimmer-blade 38 in retrimming the beginning end of the needle-thread, the cam 75 engages the nose 76 of the two-arm lever 77 and swings said two-arm lever about its pivot 78. The longer arm of the two-arm lever, being operatively connected to the shorter limb of the L-shaped lever 81, effects a rapid turning of said L-shaped lever, bringing the downturned end 82 thereof into engagement with the block 61, thereby shifting the push-rod 49 endwise against the action of the coil-spring 55 and into the position shown in Fig. 7. In this position the trimmer and nipping blades 38 and 39 are open or reset preparatory to the final trimming and nipping of the needle-thread. As shown in Fig. 7, the trimmer and nipping blades 38 and 39 are maintained in reset position by a latch-lever 83 pivoted intermediate its ends at 84 on an upstanding ear 85 formed on a bracket 86 fastened on the yoke 14 (Fig. 10). One end of the latch-lever 83 is biased, by a spring 87, downwardly to cooperate with a stop-notch 88 formed in the collar 53 which is fixed on the push-rod 49.

When the machine is started, the component parts of the thread-trimming and -nipping mechanism are in the position shown in Figs. 2 and 10. In this position, the latch-lever 83 rests upon the push-rod 49 in advance of the fixed collar 53. As the sewing progresses, the cam 67 and its associated linkage operate to effect a release of the beginning end of the thread and to retrim the released thread-end to the desired short length. As shown in Fig. 4, the extent of endwise movement imparted to the push-rod 49 to effect this thread-release and -retrim is just short of bringing the stop-notch 88 on the fixed collar 53 into register with the latch-lever 83. Consequently, the latch-lever does not preclude the proper functioning of the mechanism for this operation. Immediately after the retrim of the released thread-end is accomplished, the cam 75 and its associated linkage operate to reset the trimmer-blade 38 preparatory to its final thread-trimming and -nipping operation. As shown in Fig. 7, the extent of endwise movement imparted to the push-rod 49, in opposition to the coil-spring 55, is quite sufficient to move the stop-notch 88 on the collar 53 into register with the latch-lever 83, permitting the latch-lever under the action of the spring 87 to drop into the notch 88 and lock the trimmer-blade and nipping-blade in reset position.

Means actuated by the work-clamp lifting mechanism are provided for effecting a release of the trimmer-blade 38 and nipping-blade 39 at the end of the buttonholing cycle. Referring to Figs. 1, 2 and 7, it will be seen that the stud 24 carried by the manually controlled work-clamp elevating lever 21, and to which the treadle chain is connected, extends through a cam-slot

89 formed adjacent the upper end of an intermediate member or rock-lever 90 pivoted at 91 on the machine-bed 1. The rock-lever 90 has connected to it a link 92 having adjustably secured on it a trip-element 93 adapted to cooperate with the latch-lever 83 to lift the same out of the notch 88 when the foot-treadle is depressed to elevate the work-clamp. As shown in Figs. 1 and 2, the link 92 is also connected to one limb of a bell-crank lever 94 disposed beneath the bed 1; the other limb of the bell-crank lever being connected to a cross-slide 95 having a rack 96 in mesh with a segmental gear 97 carrying a bobbin-thread trimmer-blade 98. A copending application Serial No. 611,725 filed herewith discloses and claims the constructive features of the illustrated bobbin-thread trimmer. The connections above described function simultaneously to operate both the needle-thread trimmer and the bobbin-thread trimmer. It will be appreciated that the cam-slot 89, in its preferred form, is provided with an actuating portion 89' and a dwell-producing portion 89'' so that the link 92 is actuated only during the initial depression of the work-clamp elevating foot-treadle and during the time that the stud 24 is tracking the actuating portion 89', to insure that both of the sewing threads are cut before the work-clamp is raised to release the work. The trip 93 is adjustably fastened on the link 92 so that the timing of the release of the latch-lever 83 can be regulated. Also, the link 92 is preferably made adjustable, as shown at 99 in Figs. 1 and 2, in order to provide means for simultaneously regulating the timing of the actual thread-severing of both of the thread-trimming mechanisms.

From the above description taken in connection with the accompanying drawings, it will be appreciated that I have invented an improved means for effecting a rapid resetting of the needle-thread trimming- and nipping-blade preparatory to its final thread-trimming and -nipping action. The design of the improved means is such that its quick action is inherent. In addition, the cam for actuating the improved means is set so that it does not function until the stitches forming the return side of the button-hole are being produced. This is desirable for the reason that during the formation of the stitches on the return side of the buttonhole, the work-clamp is moving toward the standard of the machine, while the free end 82 of the lever 81 is moving away from the standard toward the approaching work-clamp. This simultaneous movement of the work-clamp and lever toward each other augments the inherent quick action of my improved resetting means, the result of which is an extremely rapid retraction of the trimmer-blade, whereby collision between the trimmer-blade and the needle is avoided when a long trimmer-blade is employed and the machine is set to sew short buttonholes approximately $\frac{1}{4}$ " in length.

Having thus set forth the nature of the invention, what I claim herein is:

1. In a group-stitch sewing machine, in combination, stitch-forming mechanism, a traveling work-clamp, a needle-thread-cutting and -nipping device, actuating means therefor including a reciprocatory element supported by and normally partaking of the movements of the work-clamp, a first means comprising a cam-actuated linkage adapted for engagement with said reciprocatory element and effective for opening and then closing said thread-cutting and

-nipping device to release and then retrim the beginning end of the needle-thread, a second means comprising another cam-actuated linkage adapted for engagement with said reciprocating element and effective for reopening said thread-cutting and -nipping device preparatory to its final nipping and cutting action, and means for effecting a final closing of said thread-cutting and -nipping device to nip and sever the needle-thread at the completion of the sewing operation.

2. In a group-stitch sewing machine, in combination, stitch-forming mechanism, a traveling work-clamp, a thread-cutting device, actuating means therefor including a reciprocatory element supported by and normally partaking of the movements of the work-clamp, means adapted for engagement with said reciprocatory element and effective for moving said thread-cutting device into open position, said means including a first pivotally mounted lever having one of its ends disposed to engage and actuate said reciprocatory element, a second pivotally mounted lever operatively connected with said first lever, and means for actuating said levers whereby the first lever moves simultaneously with and opposite to the travel of said work-clamp in actuating said reciprocatory element, and means for effecting a closing of said thread-cutting device at a predetermined time during the group-stitch cycle.

3. In a group-stitch sewing machine, in combination, a machine-frame, stitch-forming mechanism adapted for interlocking an upper thread and a lower thread, a work-clamp, means including a manually controlled lever for opening said work-clamp for the insertion and removal of work, a thread-cutting device for said upper thread and a thread-cutting device for said lower thread, a member movably mounted on said machine-frame and having a cam-slot, means on said manually controlled lever cooperating with said cam-slot for imparting movement to said member when said lever is actuated, and a connection with said member disposed to effect the operation of both of said thread-cutting devices during the initial movement of said manually controlled lever and prior to the opening of said work-clamp.

4. In a group-stitch sewing machine, in combination, a machine-frame, stitch-forming mechanism adapted for interlocking an upper thread and a lower thread, a work-clamp, means including a manually controlled lever for opening said work-clamp for the insertion and removal of work, a thread-cutting device for said upper thread and a thread-cutting device for said lower thread, a member movably mounted on said machine-frame and having a cam-slot provided with an actuating portion and a dwell-producing portion, means on said manually controlled lever cooperating with said cam-slot for imparting movement to said member during the traversing of the actuating portion of said cam-slot, and a connection with said member disposed to effect the operation of both of said thread-cutting devices during the actuation of said member.

5. In a group-stitch sewing machine, in combination, a machine-frame, stitch-forming mechanism adapted for interlocking an upper thread and a lower thread, a work-clamp, means including a manually controlled lever for opening said work-clamp for the insertion and removal of work, a thread-cutting device for said upper thread and a thread-cutting device for said lower

thread, a member movably mounted on said machine-frame and having a cam-slot provided with an actuating portion and a dwell-producing portion, means on said manually controlled lever cooperating with said cam-slot for imparting movement to said member during the traversing of the actuating portion of said cam-slot, a connection with said member disposed to effect the operation of both of said thread-cutting devices during the actuation of said member, and means for simultaneously regulating the timing of the thread-severing of both of said thread-cutting elements.

6. In a group-stitch sewing machine, in combination, a machine-frame, stitch-forming mechanism adapted for interlocking an upper thread and a lower thread, a work-clamp, means including a manually controlled lever for opening said work-clamp for the insertion and removal of work, a thread-cutting device for the upper thread and a thread-cutting device for the lower thread, a member movably mounted on said machine-frame and having a cam-slot provided with an actuating portion and a dwell-producing portion, means on said manually controlled lever cooperating with said cam-slot for imparting movement to said member during the traversing of the actuating portion of said cam-slot, a connection with said member disposed to effect the operation of both of said thread-cutting devices during the actuation of said member, and means for regulating the time of thread-severing of one of said thread-cutting devices relative to the time of thread-severing of the other of said thread-cutting devices.

7. In a group-stitch sewing machine, in combination, a machine-frame, stitch-forming mechanism, a work-clamp, means including a manually controlled lever for opening said work-clamp for the insertion and removal of work, a thread-cutting device, means for opening said thread-cutting device, a latch for maintaining said thread-cutting device in open position, a member movably mounted on said machine-frame and having a cam-slot provided with an actuating portion and a dwell-producing portion, means associated with said work-clamp opening means and cooperating with said cam-slot for imparting movement to said member during the traversing of the actuating portion of said cam-slot, and a connection with said member disposed to trip said latch during the actuation of said member whereby said thread-cutting device is released to close into effective thread-severing position.

8. In a group-stitch sewing machine, in combination, a machine-frame, stitch-forming mechanism adapted for interlocking an upper thread and a lower thread, a work-clamp, means including a manually controlled lever for opening said work-clamp for the insertion and removal of work, a thread-cutting device for said upper thread and a thread-cutting device for said lower thread, a member movably mounted on said machine-frame and having a cam-slot provided with an actuating portion and a dwell-producing portion, means on said manually controlled lever cooperating with said cam-slot for imparting movement to said member during the traversing of the actuating portion of said cam-slot, said actuating portion of the cam-slot being disposed so that said member is shifted the full extent of its movement before said work-clamp is opened sufficiently to free the work, and a connection with said member disposed to effect the operation

of both of said thread-cutting devices during the actuation of said member.

9. In a sewing machine, in combination, stitch-forming mechanism, a work-clamp, feeding means for relatively moving the stitch-forming mechanism and the work-clamp to sew a group of stitches, said feeding means including an actuating feed-shaft, a needle-thread-cutting and -nipping device, an actuating member operatively associated with said needle-thread-cutting and -nipping device, a first means actuated from said feed-shaft for engagement with said actuating member for opening and closing said thread-cutting and -nipping device to release and then retrim the beginning end of the needle-thread, a second means also actuated from said feed-shaft for engagement with said actuating member for reopening said thread-cutting and -nipping device preparatory to its final nipping and cutting action, and means permitting a final closing of said thread-cutting and -nipping device to nip and sever the needle-thread at the completion of the sewing operation.

10. In a sewing machine, in combination, stitch-forming mechanism, a work-clamp, feeding means for relatively moving the stitch-forming mechanism and the work-clamp to sew a group of stitches, said feeding means including an actuating feed-shaft, a needle-thread-cutting and -nipping device, an actuating member operatively associated with said needle-thread-cutting and -nipping device, a first means adapted to engage said actuating member for opening and closing said thread-cutting and -nipping device to release and then retrim the beginning end of the needle-thread, a second means adapted to engage said actuating member for reopening said thread-cutting device preparatory to its final nipping and cutting action, a single actuating device secured on said feed-shaft for operating said first and second means in series, and means permitting a final closing of said thread-cutting and -nipping device to nip and sever the needle-thread at the completion of the sewing operation.

11. In a sewing machine, in combination, stitch-forming mechanism, a work-clamp, feeding means for relatively moving the stitch-forming mechanism and the work-clamp to sew a group of stitches, said feeding means including a feed-shaft and connections for varying the extent of the relative movement between the stitch-forming mechanism and the work-clamp, a needle-thread-cutting and -nipping device, an actuating member operatively associated with said needle-thread-cutting and -nipping device, a first means adapted to engage said actuating member for opening and closing said thread-cutting and -nipping device to release and then retrim the beginning end of the needle-thread, a second means adapted to engage said actuating member for reopening said thread-cutting and -nipping device preparatory to its final nipping and cutting action, an actuating device for operating said first and second means in series, means for regulating the effective position of said actuating device to conform with the selected position of adjustment of the connections for varying the extent of relative movement between the stitch-forming mechanism and the work-clamp, and means for permitting a final closing of said thread-cutting and -nipping device to nip and sever the needle-thread at the completion of the sewing operation.

12. In a sewing machine, in combination, stitch-forming mechanism, a work-clamp, feeding means

for relatively moving the stitch-forming mechanism and the work-clamp to sew a group of stitches, said feeding means including an actuating feed-shaft, a needle-thread-cutting and -nipping device, an actuating member operatively associated with said needle-thread-cutting and nipping device, a first means adapted to engage said actuating member for opening and closing said thread-cutting and -nipping device to release and then retrim the beginning end of the needle-thread, a second means adapted to engage said actuating member for reopening said thread-cutting device preparatory to its final nipping and cutting action, an actuating device secured on said feed-shaft and having a plurality of cam-sections disposed to operate said first and second means in series, and means permitting a final closing of said thread-cutting and -nipping device to nip and sever the needle-thread at the completion of the sewing operation.

13. In a sewing machine, in combination, stitch-forming mechanism, a work-clamp, feeding means for relatively moving the stitch-forming mechanism and the work-clamp to sew a group of stitches, said feeding means including a feed-shaft and connections for varying the extent of the relative movement between the stitch-forming mechanism and the work-clamp, a needle-thread-cutting and -nipping device, an actuating member operatively associated with said needle-thread-cutting and -nipping device, a first means adapted to engage said actuating member for opening and closing said thread-cutting and -nipping device to release and then retrim the beginning end of the needle-thread, a second means adapted to engage said actuating member for reopening said thread-cutting and -nipping device preparatory to its final nipping and cutting action, an actuating device provided with a plurality of cam-sections disposed to operate said first and second means in series, said actuating device being mounted on said feed-shaft and secured thereto by means permitting regulation of the effective position of said cam-sections to

conform with the selected position of adjustment of the connections for varying the extent of relative movement between the stitch-forming mechanism and the work-clamp, and means for permitting a final closing of said thread-cutting and -nipping device to nip and sever the needle-thread at the completion of the sewing operation.

14. In a group-stitch sewing machine, in combination, stitch-forming mechanism, a traveling work-clamp, a thread-cutting device, an actuating member operatively associated with said thread-cutting device and supported by the normally partaking of the movements of the work-clamp, means adapted for engagement with said actuating member and effective for moving said thread-cutting device into open position, said means including a first pivotally mounted lever having one of its ends disposed to engage and operate said actuating member, a second pivotally mounted lever connected to said first lever, and a cam device engaging said second lever in a manner to move said lever simultaneously with and opposite to the travel of said work-clamp in operating said actuating member, and means for effecting a closing of said thread-cutting device at a predetermined time during the machine cycle.
